UNITED STATES PATENT OFFICE.

LAWRENCE C. SOULE, OF BUFFALO, NEW YORK, ASSIGNOR TO AMERICAN RADIATOR COMPANY, OF CHICAGO, ILLINOIS, A CORPORATION OF NEW JERSEY.

HEATING UNIT.

Application filed October 8, 1920. Serial No. 415,470.

To all whom it may concern:

Be it known that I, LAWRENCE C. SOULE, a citizen of the United States, residing at Buffalo, in the county of Erie and State of New York, have invented new and useful Improvements in Heating Units, of which the following is a full, clear, concise, and exact description, reference being had to the accompanying drawing, forming a part 10 of this specification.

My invention relates to improvements in heating apparatus and particularly to that type of apparatus used for factories, schools, and auditoriums and the like.

15 One of the objects of my invention is to provide a heating unit through which the air, either of the room, or from the outside, or both, may be passed over the heat emitting surface and heated before it is discharged into the room.

Another object of my invention is to provide a heating unit which may be readily assembled, which will not only indirectly heat the air, but which also will have a certain 25 amount of direct radiating surface.

Another object of my invention is to provide a readily assembled device in which the air as it passes therethrough will pass over or "wipe" a large amount of heating surface.

30 For the purpose of disclosing my invention I have illustrated one embodiment thereof in the accompanying drawings in which,

Fig. 1 is a central vertical sectional view 35 illustrating one embodiment of my invention,

Fig. 2 is a front elevation thereof,

Fig. 3 is a sectional view taken on the line 3—3 of Fig. 1,

40 Fig. 4 is a rear elevation of the embodiment, and

Fig. 5 is a sectional view taken on the line 5—5 of Fig. 4.

In the embodiment illustrated, I provide 45 a base 1 which is hollow and preferably rectangular in shape and provided with legs 1^a to suitably raise it from the floor. The bottom of this base is partially closed by a wall 2, the top being open and having on 50 the inner face of the sides thereof a horizontally disposed flange 3 which is somewhat below the top. One of the sides of the base is provided with an opening surrounding 55 which is a flange 4 adapted to receive a conduit pipe 5. This pipe leads to the outer air

and the opening in the base is controlled by damper 6 pivotally mounted in position. A second inlet opening 7 in the bottom of the base is provided which opening is likewise controlled by a damper 8, the two dampers being connected by a link 9 so that they will move in unison, the connection being such however, that as the damper 6 is open the damper 8 is closed and vice versa.

For operating the dampers, the pivot 10 on which the damper 8 is mounted is provided with an arm 11 arranged on the exterior of the base which arm is adapted to be rocked back and forth by the operator to move the dampers to any desired position. 70 This arm 11 is provided with a locking device for a positive setting of the dampers.

The air heating element of the heater unit comprises a flue composed of a plurality of sections 12, Fig. 5, mounted one on top of 75 the other, and on top of the base, through which steam or hot water is adapted to circulate. The sections are all alike and each comprises a pair of hollow peripheral side members 13 connected at their ends to hollow peripheral cross heads 14. Extending between the cross heads 14 are parallel hollow ribs 15 which are oval shaped in cross section.

The ribs 15 are spaced apart and from one side member equidistantly although the space between the opposite side member and its adjacent rib is greater. An intermediate cross member 15^a also connects the ribs and side members.

At a point equidistant from the side members there are provided nipple openings 16 by which each section of the apparatus is connected with the others so that the heating fluid after circulating through one section 90 may pass into the next one above.

The side and end members as well as the ribs are preferably oval shaped as shown in Fig. 3 so that a minimum amount of resistance will be offered to the air as it passes up through the sections. Around the outer edges of the sections on both the top and bottom, as well as surrounding the nipple connections, there are provided fins 17 which form meeting edges when the sections 95 are stacked one upon the other whereby the sides of the flue formed by the sections are completely closed.

In assembling the apparatus a bottom section is laid upon the ledge or flange 3 in the 110

- base, the rest of the sections are stacked one on top of the other, the fins 17 making a tight joint between the sections. In stacking the sections, every alternate section is 5 reversed so that while the nipple connections 16 are in alignment the ribs are staggered with respect to one another, forming a tortuous path through the flue for the air. Suitable nipples 18 connect the various sections together and the top section is provided with a connection 19 for the admission 10 of steam or hot water, while the bottom section is provided with a connection 20 for the return flow of the steam or hot water. 15 On the top of this return connection an air vent pipe 37 is provided with a large opening air valve 38 on the end of the vent pipe. The heater construction insures quick venting of the entire heater. 20 Mounted upon the top of the flue thus built up is a hood or cover, the base 21 of which is rectangular in shape and is provided with a flange 22 adapted to rest upon the top section of the radiating sections. 25 One side 23 of the top or cover is provided with a suitable circular opening having an annular flange 24 surrounding the same over which may be fitted a flue 25 or if desired the flue may be dispensed with. 30 A suitable bracket consisting of a vertically extending brace 26 and a transversely extending brace 27 formed integrally with the side 23 and forming at their junction a bearing 28 is provided in the opening. The 35 rear side of the top or cover is arc shaped as at 29 and is provided with an opening covered by a removable plate 30. Mounted on the cover 21 is a suitable driving motor 31, the shaft of which passes 40 through the plate 30 and the opposite end of which shaft is mounted in the bearing 28. This shaft is provided with a blower fan 32 adapted to produce a forced draft through the heating unit. It is obvious that 45 instead of driving the fan 32 with electric motor 31 other means for operating the fan may be provided. The whole unit thus constructed and comprising the top, base and flues, is tied together by suitable tie rods 33 which pass 50 through lugs 34 extending laterally from the top and bottom and are provided with nuts 36.
- The operation of the device is apparent. 55 The unit is placed in any desired position and by means of the flue 5 is connected with the outside atmosphere. The steam or hot water is admitted to the radiating sections and as the fan 32 is operated, the air is 60 drawn into the bottom of the base of the unit, passing up through the heating sections and, due to the staggered arrangement of the ribs thereof, wipes across a large number of radiating ribs and finally passes 65 out through the eduction opening in the top

of the unit. If desired the room air may be re-heated by closing the damper 6 and opening the damper 8, or if desired the room air and fresh air may be mixed by partially opening one of the dampers and partially closing the other. The air current may be exactly reversed, if desired, by changing the direction of rotation of the fan. 70

It will be noted that in addition to the radiating surface provided for heating the air as it passes through the unit there is also provided a direct radiating surface on the exterior of the unit which aids in heating the air of the room. 75

Having thus described my invention, 80 what I claim as new and desire to secure by Letters Patent is:—

1. In a heating unit, the combination with a hollow base having an air induction port therein, of an air heating flue mounted on said base open from top to bottom and comprising a plurality of sections each comprising a plurality of parallel hollow ribs connected at their ends by headers, the headers and outer parallel ribs of each section being adapted to meet face to face to form the closed side walls of said flue, and a cover for said flue having an eduction port. 85

2. In a heating unit, the combination with a hollow base having an air induction port therein, of an air heating flue mounted on said base and comprising a plurality of fluid circulating sections placed one on top of the other, each section comprising hollow side members connected together by hollow end members and parallel hollow ribs extending between the end members parallel with the side members, the space between one side member and its adjoining rib being greater than the space between the ribs and the opposite side member and adjacent rib, and the end members having circulating openings therein equidistant from each side member, and a cover surmounting said flue having an air eduction port therein. 100

3. In a heating unit, the combination with a hollow base, of an air heating flue mounted on said base comprising a plurality of sections placed one on top of the other and each comprising hollow peripheral members having inlet and outlet openings equidistant from each side, a plurality of hollow parallel connecting ribs extending between said peripheral members equally spaced apart from one another and from one side of the peripheral member but unequally spaced apart from the other side of the peripheral member, and a cover for said flue having an air eduction port. 115

4. In a heating unit, the combination with a hollow base, of a heating flue comprising a plurality of fluid containing sections placed one on top of the other, mounted on 120

5 said base, each section comprising hollow parallel end members, hollow parallel side members, intermediate hollow parallel ribs extending between the side members and a continuous fin on the opposite faces of said end and side members arranged to abut when the sections are connected to form a continuous flue, and a hollow top surmounting said flue and having an air eduction 10 port.

15 5. In a heating unit, the combination with a hollow base having an air induction port therein, of a heating flue mounted on said base and comprising a plurality of fluid circulating sections connected together, each section comprising hollow parallel end and side members and parallel hollow ribs extending between said members, said members and ribs being greater 20 in width at their center in cross sections than at their tops and bottoms, and a cover surmounting said flue and having an air eduction port therein.

25 6. In a heating unit, the combination with a hollow base having an air induction port therein, of a heating flue mounted on said base and comprising a plurality of fluid circulating sections mounted one on top of the other, each section comprising hollow parallel side and end members having a continuous fin formed on their opposite faces adapted to abut when the sections are connected together, and intermediate hollow ribs connecting said side and end 30 members.

40 7. In a heating unit, the combination with a hollow base having an air induction port therein, of a heating flue mounted on said base comprising a plurality of fluid circulating sections mounted one on top of the other, each section comprising hollow peripheral sections having fins on the opposite faces thereof adapted to abut when the sections are placed face to face, and hollow parallel ribs arranged within said peripheral members, and a top surmounting said flue having an air eduction port 45 therein.

50 8. A fluid circulating radiating section comprising parallel hollow end members, parallel hollow side members and a plurality of hollow parallel ribs extending between said end members, said ribs being spaced apart an equal distance from one another, and the rib adjacent to one side member being spaced therefrom a distance equal to the distance between said ribs, and the rib adjacent to the other side member being unequally spaced with reference to said 55 last named side member; said end members having circulating openings therein arranged equidistantly from said side members.

60 9. In a heating unit, the combination with a hollow rectangular base having an

air induction port therein and having near its top an inwardly extending flange on each of its sides, of an air heating flue supported on said flange and comprising a plurality of rectangular sections mounted 70 one upon the other, each section having side members and end members and parallel rib members, said sections all being circumferentially connected, a top for said flue having a rectangular base provided with an in- 75 turned flange resting on said flue section, an air eduction port in said top, and a fan mounted to operate in said top and cause a forced draft of the air from the bottom upwardly through the heating flue and out the 80 eduction port.

10. In a heating unit, the combination with a base having an induction port therein, of a heating flue comprising a plurality of sections placed, one on top of the 85 other, each section comprising hollow peripheral members, and hollow parallel ribs extending between the peripheral members, the ribs of each section being staggered with respect to the ribs of the next section. 90

11. In a heating unit, the combination with a hollow base having an air induction port therein, means for controlling the admission of air therethrough, of an air heating flue mounted upon said base open from top to bottom and comprising a plurality of sections each comprising headers and a plurality of parallel hollow ribs connected at their ends to said headers, the headers and outer parallel ribs of each section being 95 adapted to meet face to face to form the closed side walls of said flue, a cover for said flue having an air eduction port therein, and means arranged in said cover for inducing a circulation of air through said 100 base, flue and cover, substantially as specified.

12. In a heating unit, the combination with a hollow base having an air induction port therein, means for controlling the admission of air therethrough, of an air heating flue mounted upon said base open from top to bottom and comprising a plurality of sections each comprising headers and a plurality of parallel hollow ribs connected 110 at their ends to said headers, the headers and outer parallel ribs of each section being adapted to meet face to face to form the closed side walls of said flue, a cover for said flue having an air eduction port therein, a fan blower mounted in said cover, and a motor connected to said blower for actuating the same whereby to induce a circulation of air through said base, flue and 115 cover, substantially as specified. 120

13. An apparatus of the character described comprising a hollow base having an air induction port therein, a heat emitting member mounted upon said base; said heat emitting member comprising a plurality of 130

superposed reticular sections of corresponding outline whose contacting peripheral wall portions constitute the side walls of said heating member and whose interior portions 5 constitute a flue, and a cover for said heating member having an air eduction port therein, substantially as specified.

14. An apparatus of the character described comprising a hollow base having 10 an air induction port therein, means for controlling the admission of air thereto, a heat emitting member mounted upon said base; said heat emitting member comprising a plurality of superposed reticular sections 15 of corresponding outline whose contacting peripheral wall portions constitute the side walls of said heating member and whose interior portions constitute a flue, a cover for said heat emitting member having an air eduction port 20 therein, and means arranged in said cover for inducing a circulation of air through the apparatus, substantially as specified.

15. An apparatus of the character described comprising a hollow base having a 25 plurality of air induction ports therein, a valve for each of said induction ports, means connecting said valves whereby simultaneously to operate the same, a heat emitting member mounted upon said base; said heat emitting member comprising a plurality of 30 superposed reticular sections of corresponding outline whose contacting peripheral wall portions constitute the side walls of 35 said heating member and whose interior portions constitute a flue, a cover for said heat emitting member having an air eduction port therein, a blower supported in said cover, and means for actuating said 40 blower whereby to induce circulation of air through said apparatus, substantially as specified.

16. An apparatus of the character described comprising a hollow base having an 45 air induction port therein, an air heating flue mounted upon said base and comprising a plurality of sections each composed of hollow end members and a plurality of transverse hollow ribs connected at their 50 opposite ends to said hollow end members; the outer of said transverse hollow ribs and said hollow end members being adapted to contact and form the closed side walls of said flue, and a cover for said flue having 55 an air eduction port, substantially as specified.

17. An apparatus of the character described comprising a hollow base having an 60 air induction port therein, an air heating flue mounted upon said base comprising a plurality of sections each composed of hollow end members, and a plurality of transverse hollow ribs connected at their ends to said hollow end members; the outer of 65 said transverse hollow ribs and said hollow

end members being arranged in superposed relation and forming the closed side walls of said flue, and a cover for said flue having an air eduction port therein, substantially as specified.

18. An apparatus of the character described comprising a hollow base having an air induction port therein, means for controlling the admission of air thereto, an air heating flue mounted upon said base 75 comprising a plurality of sections each composed of hollow end members, and a plurality of transverse hollow ribs connected at their ends to said hollow end members; the outer of said transverse hollow ribs and 80 said hollow end members being arranged in superposed relation and forming the closed side walls of said flue, a cover for said flue having an air eduction port therein, and means arranged in said cover for 85 inducing circulation of air through the apparatus, substantially as specified.

19. An apparatus of the character described comprising a hollow base having air induction ports therein, valve means for simultaneously controlling the admission of air through said induction ports, an air heating flue mounted upon said base and comprising a plurality of sections of similar outline, and each section composed of hollow end 90 members and a plurality of transverse hollow ribs connected at their ends to said hollow end members; the outer of said transverse hollow ribs and said hollow end members being adapted to contact with the corresponding portions of the adjacent sections and form therewith the closed outer walls 95 of said flue, and a cover for said flue having an air eduction port therein, substantially as specified.

20. An apparatus of the character described comprising a hollow base having air induction ports therein, a valve for each of said ports, means connecting said valve whereby simultaneously to control the operation thereof, an air heating flue mounted upon said base and comprising a plurality of sections of similar outline, and each section composed of hollow end members and a plurality of transverse hollow ribs connected at 110 their ends to said hollow end members; said sections being arranged in superposed relation and the outer of said transverse hollow ribs and said hollow end members being adapted to contact with the corresponding portions of the adjacent sections and form therewith the closed outer walls of said flue, 115 means for securing said sections in assembled relation, a cover for said flue having an air eduction port therein, a blower in said 120 cover, and means for actuating said blower whereby to induce a circulation of air through the apparatus, substantially as specified.

21. In a heating unit, the combination 125

with a hollow rectangular base having an air induction port therein, valve means for controlling the passage of air therethrough, of an air heating flue supported upon said base comprising a plurality of rectangular sections mounted one upon the other, each section having side members and end members and parallel rib members, said sections all being circulating connected, a top for said flue having a rectangular base support- ed on the top of said flue, an air eduction port in said top, a fan blower mounted in said top, and a motor for actuating said blower whereby to cause a forced draft of air from the bottom upwardly through the 15 heating flue and the eduction port in said top, substantially as specified.

In witness whereof, I have hereunto subscribed my name.

LAWRENCE C. SOULE.
